CONTROL MECHANISM FOR SEWING
MACHINES AND THE LIKE

Philip B. Clark, Morton Grove, Ill., assignor to
Union Special Machine Company, Chicago, Ill.,
a corporation of Illinois

Application April 12, 1945, Serial No. 587,973

13 Claims. (Cl. 112—11)

1

This invention relates to sewing machines and the like, and more particularly to such machines for closing filled bags and having a control mechanism for placing various devices embodied in the machine in and out of service under predetermined conditions and in a desired sequence.

It is an important object of this invention to provide a filled bag closing machine, wherein a conveyor transports a filled bag having an open end up to and past a mechanism for closing the open end of the bag, with a control device capable of readily placing both the conveyor and the mechanism into active service and for successively placing the mechanism and the conveyor out of service under certain conditions.

Another object of the invention is to provide a machine of the character indicated with a control apparatus for manually placing various devices of the machine in service and for subsequently automatically placing those devices out of service in a desired sequence and under predetermined conditions.

Another object of the invention is to provide an improved sewing machine or the like for closing a filled bag or other article, which machine performs its intended functions in an effective, efficient and trouble-free manner.

A further object of the invention is the provision of a unitary filled bag closing machine that may be readily moved from place to place as required by conditions in a plant where the machine is used.

A still further object of the invention is to provide a machine of the character indicated, including a conveyor and a bag closing mechanism which are relatively adjustable and which are provided with suitable control devices.

An additional object of the invention resides in the provision of a portable filled bag closing machine that is relatively simple and compact in design, sturdy in construction, and inexpensive to manufacture and maintain.

The machine of this invention may include a lower frame mounted on swivel casters and supporting an upper frame that carries an overhanging mechanism adapted to close a filled bag. Carried by the lower frame and extending to one side thereof and beneath the bag closing mechanism is an endless conveyor for carrying a filled bag up to and past the closing mechanism. Both the bag closing mechanism and the conveyor are vertically adjustable in order to accommodate various sizes of filled bags. A single prime mover, preferably an electric motor, operates a double clutch arrangement for successively placing the

2

conveyor and bag closing mechanism into active service and for subsequently successively placing the bag closing mechanism and the conveyor out of active service. This double clutch arrangement is responsive to movement of a member such as a rotary shaft. Upon predetermined rotation of this shaft in one direction, the conveyor and bag closing mechanism are successively placed in service. Upon subsequent rotation of this shaft in a reverse direction the bag closing mechanism and conveyor are successively placed out of service.

An arrangement of devices controls the operation of the above mentioned shaft and includes a foot treadle adapted to be depressed, thereby 10 rotating the shaft in a direction to place the conveyor and sewing machine successively into service. Upon release of the foot treadle, the shaft is automatically rotated to a predetermined extent in a reverse direction, whereby the double 15 clutch arrangement is actuated in a manner to place only the bag closing mechanism out of service. Suitable releasable detent means prevent further rotation of the shaft in the reverse direction. An element secured to the detent means extends into the path of travel of a filled bag on the conveyor. When the filled bag in the course of 20 its travel on the conveyor bears against this element, it actuates the latter, causing release of the detent means and thereby allowing continued 25 rotational movement of the shaft in the reverse direction with the result that the clutch arrangement is actuated in a manner to place the conveyor out of service.

With the above and other objects in view, the 30 invention comprises the devices, combinations and arrangements of parts set forth in the following detailed description and illustrated in the annexed drawings of a preferred embodiment of the invention, from which the several features of 35 the invention, together with the advantages attainable thereby, will be readily understood by persons skilled in the art.

In the drawings:

Figure 1 is a view of the machine of this invention in side elevation and with parts broken away for better illustration;

Figure 2 is a front elevational view of the machine of the invention partly in vertical cross section and with parts omitted;

Figure 3 is an enlarged fragmentary view of a control arrangement in front elevation with the cover plate removed;

Figure 4 is a top plan view of Figure 3;

Figure 5 is a cross-sectional view taken along

line 5—5 in Figure 3 and showing the cover plate in position; and

Figures 6, 7 and 8 illustrate several relative positions of a pair of elements of a detent means.

Referring now to the drawings, wherein like reference characters denote corresponding parts throughout the several views, and more particularly to Figures 1 and 2, the machine of the invention includes a lower frame 10, consisting essentially of a base 11, supported at each corner on a swivel caster 12, spaced vertical supports 13, and a top 14. Mounted on lower frame 10 and extending upwardly therefrom is a hollow upper frame or housing 15 that carries a bag closing mechanism, such as a mechanical sewing machine, generally indicated by numeral 16. Sewing machine 16 is removably secured to upper frame 15 and overhangs a side face thereof.

A hand wheel 18 is secured by set screws 19 to one end of a shaft 20 that is rotatably supported in a bracket 21 and that carries a pulley 22 at its other end. A weight 23 is vertically movable within upper frame 15 and is connected to one end of a cable 24 that engages pulley 22 and that is connected at its other end to bag closing mechanism 16. Weight 23 serves to counterbalance the weight of bag closing mechanism 16 to facilitate the manual vertical adjustment of the bag closing mechanism. It will be noted that with the arrangement just described, bag closing mechanism 16 may be readily raised or lowered depending upon the direction of rotation of handwheel 18.

A prime mover, such as an electric motor 25 (Figure 1), is mounted on lower frame 10 and includes a substantially vertical shaft 27 that carries a drive pulley 28. Rotation of shaft 27 is transmitted by drive pulley 28 and a belt 29 to combined pulley and lower female clutch member 30. Combined pulley and female clutch member 30 is freely slideable along and rotatable about the axis of a vertical shaft 31. A lower male clutch member 32 is secured by a set screw 33 to the upper portion of shaft 31. Shaft 31 extends through a cover 35 and carries at its upper end an upper male clutch member 36 that is adapted to be moved into and out of engagement with an upper female clutch member 37, coupled by a connector 38 and a set screw 39 to the lower end of a shaft 40. It will be noted that shafts 31 and 40 are co-axial. A pulley 41, affixed to the upper portion of shaft 40, drives a sewing machine pulley 26 through the medium of a V-belt 42 (Figure 1).

A depending L-shaped bracket 43 (Figure 2) is mounted within the confines of lower frame 10 and is connected by a pivot 44 to a lever 45. One end 46 of lever 45 projects into an annular groove 47 formed in a sleeve 48 that embraces shaft 31 and is slideable along the axis thereof. A spring 49 is fastened to the under side of lower frame top 14 and to the other end 50 of lever 45. Spring 49 is at all times in tension, and as viewed in Figure 2, normally urges lever 45 in a counter-clockwise direction. An arm 51 is preferably formed integral with lever 45 and has a brake 52 that normally bears against the outer surface of lower male clutch member 32 due to the action of spring 49. When lever 45 is rotated in a clockwise direction (Figure 2) about pivot 44 against the action of spring 49, by devices which will be described further along, sleeve 48 is moved upwardly along shaft 31 to first place combined pulley and lower female clutch member 30 into engagement with lower male clutch member 32,

thereby imparting rotation to shaft 31. Continued movement of lever 45 in a clockwise direction next brings upper male clutch member 36 into engagement with upper female clutch member 37, thereby imparting rotation to shaft 40 and thence, through pulley 41 and belt 42, to bag closing mechanism pulley 26, whereby mechanism 16 is placed in active service. When lever 45 is urged in a counter-clockwise direction (Figure 2) by spring 49, its end 46 moves sleeve 48 downwardly along shaft 31. At such a time upper male clutch 36 is first disengaged from upper female clutch member 37 and then combined pulley and lower female clutch member 30 is disengaged from lower male clutch member 32. The clutch members just described and the devices for actuating the same to place them into and out of engagement may be the same or similar to those disclosed in the patent to F. Lutz, 1,791,419, granted February 3, 1931, to which reference is had for further details as to construction and operation.

Reference is next had to Figures 1 and 2 for details of construction of a conveyor assembly 55, which includes a frame 56 that supports a pair of substantially parallel horizontal shafts 57, each of which carries a pulley 58 for imparting movement to a flexible endless conveyor belt 59. A leg 60 is fastened to the free end of each shaft 57 and is adjustable horizontally and vertically with respect to its corresponding shaft as allowed by slots 61 and 62, respectively. Also secured to conveyor frame 56 is a shelf 65 having a smooth upper surface along which the under surface of conveyor belt 59 is adapted to slide with a minimum of friction during operation.

The conveyor assembly 55 may be raised and lowered at the will of the operator by an arrangement of devices that will now be described. Tapped lugs 66, attached to conveyor frame 56 (Figure 1), are in threaded engagement with vertical screw shafts 67 that are positioned within lower frame 10. Secured to the upper end of each screw shaft 67 and rotatable therewith is a bevel gear 68 that mates with a corresponding bevel gear 69 affixed to a horizontal shaft 70 that is operated by a hand crank 71. It will be apparent that upon manual operation of crank 71, shaft 70, bevel gears 69, bevel gears 68 and screw shafts 67 cooperate with threaded lugs 66 to either raise or lower conveyor assembly 55, depending upon the direction of rotation of crank 71. Conveyor assembly 55 may be lowered until legs 60 rest on the floor when the machine of this invention is in use. When it is desired to move the entire machine to another part of the plant, the operator merely turns crank 71 to raise conveyor assembly 55 any desired distance above the floor, permitting the machine to be rolled on swivel casters 12.

The lower portion of vertical shaft 31 extends into a housing 75 which contains a gear train (not shown) for translating rotation of vertical shaft 31 into rotation of a horizontal shaft 76, that is fastened to a sprocket wheel 77 by a key 78, or the like. A second sprocket wheel 79 is affixed to left hand conveyor pulley 58 as viewed in Figure 2 and is actuated by sprocket wheel 77 through the medium of an endless chain 80.

A member or shaft 81 is rotatably supported in the lower part of frame 10 and a lever 82 (Figures 1 and 2), rotatable therewith, is connected at its free end by a turnbuckle pitman 83 to end 50 of lever 45. It will be noted that upon rotation of member 81 in a counter-clockwise

direction (Figure 2) lever 45 is actuated in a clockwise direction against the action of spring 49 to thereby place the conveyor belt 59 and the bag closing mechanism 16 successively into service. Upon return rotation of member 81 in a reverse direction, lever 45 is moved in a counter-clockwise direction by spring 49.

Actuation of member 81 is controlled by devices that will now be described with particular reference to Figures 3, 4 and 5. As is shown in Figure 3, a portion of member 81 extends through a side wall 84 of a control frame 85 that includes a base 86, end walls 87 and a partial front cover 88. A connector block 89 is secured to member 81 and to a rod 90 by set screws 91 and 92, respectively. A foot treadle 93 is attached to one end of rod 90.

One of the outstanding features of the invention resides in the provision of releasable detent means for controlling the movement of rod 90 and therefore member 81 in one direction. This detent means includes a block or dog 95 adjustably secured to rod 90, intermediate connector block 89 and foot treadle 93, by a set screw 96 and having a notch 97. A pawl 98, adapted to be placed into and out of registration with notch 97 in block 95, is adjustably attached to a pawl shaft 99 that is rotatably supported in end walls 87. A block 100 is adapted to be attached to pawl shaft 99 at any desired point therealong by a set screw 101. Adjustably secured to block 100 by a set screw 102 is an upstanding rod 103 that has a block 104 attached to its upper portion by a set screw 105. The block 104 is also bored to receive a curved element or finger 106 that is maintained in desired position by a set screw 107. It will be noted that finger 106 is disposed above conveyor belt 59 and extends into the path of travel of a filled bag B, having an open end E, that is to be closed by mechanism 16. A spring 108 is fastened at its upper end to pawl 98 by a screw 109 and at its lower end to base 86 by a screw 110. Spring 108 is in tension and tends to normally urge pawl 98 in a clockwise direction as viewed in Figure 5.

Several relative positions of dog 95 and pawl 98 are illustrated in Figures 6, 7 and 8. Figure 6 depicts the relative position of dog 95 and pawl 98 when conveyor belt 59 and bag closing mechanism 16 are idle. Dog 95 and pawl 98 are shown in locking engagement in Figure 7, this being the relative position of these elements at such times as conveyor belt 59 is in service and bag closing mechanism 16 is idle or out of service. Figure 7 shows dog 95 and pawl 98 in a relative position corresponding to that indicated in Figures 3 and 5. When both the conveyor belt 59 and bag closing mechanism 16 are in service, dog 95 and pawl 98 assume the relative position shown in Figure 8.

For the purpose of briefly discussing the mode of operation of the machine, it is first assumed that electric motor 25 is in continuous operation thereby imparting rotation to combined pulley and lower female clutch member 30 through the medium of shaft 27, pulley 28 and belt 29. Let us next assume that lever 45 is in the relative position shown in Figure 2, that both bag closing mechanism 16 and endless conveyor belt 59 are out of service, and that a filled bag is on the conveyor assembly 55 in a position ready to be closed. The operator depresses foot treadle 93 imparting rotation to member 81, thereby rotating lever 45 in a counter-clockwise direction

(Figure 2) against the action of spring 49. As end 46 of lever 45 moves upwardly, it carries with it sleeve 48 which moves combined pulley and lower female clutch member 30 upwardly into engagement with lower male clutch member 32, causing shaft 31 to rotate which in turn imparts movement to conveyor belt 59 through horizontal shaft 76, sprocket wheel 77, endless chain 80, sprocket wheel 79, and conveyor pulleys 58, in the order named. Continued upward movement of sleeve 48 correspondingly moves upper male clutch member 36 into engagement with upper female clutch member 37 and imparting rotation to shaft 40 to thereby place bag closing mechanism 16 into service through the medium of pulley 41, belt 42 and pulley 26 in the order named. With bag closing mechanism 16 and conveyor belt 59 thus in service, the bag is moved along the conveyor assembly 55 and simultaneously stitched or otherwise closed by mechanism 16. As soon as the bag closing operation is completed, the operator releases foot treadle 93 which is moved upwardly by member 81 due to the action of spring 49, lever 45 simultaneously being urged in a counter-clockwise direction (Figure 2), sleeve 48 moving downwardly permitting disengagement between upper male clutch member 36 and upper female clutch member 37 to place bag closing mechanism 16 out of service. At this time upward movement of rod 90 is arrested by the detent means due to the locking engagement of pawl 98 with dog 95 as indicated in Figures 3, 5 and 7. This permits continued operation of the conveyor assembly.

Under the conditions just described, conveyor belt 59 continues to move in the direction indicated by the arrow until the next filled bag carried thereon strikes finger 106, swinging rod 103 in a direction away from the conveyor belt and imparting sufficient rotation to shaft 99 to rotate pawl 98 out of notch 97 against the action of spring 108. The detent means being thus released, rod 90 continues to move upwardly through its connections with spring 49, thereby permitting continued rotation of lever 45 in a counterclockwise direction (Figure 2) to permit disengagement between combined pulley and lower female clutch 30 and lower male clutch member 32, thereby placing the conveyor assembly 55 out of service. The above described cycle of operation is then repeated.

Although the invention has been herein shown and described in simple and practicable form, it is recognized that certain parts or elements thereof are representative of other parts or elements which may be used in substantially the same manner to accomplish substantially the same results. Therefore, it is to be understood that the invention is not to be limited to the exact details described herein, but is to be accorded the full scope and protection of the appended claims.

I claim:

1. In apparatus of the character described, a conveyor adapted to carry a bag having an open end, a mechanism for closing said open end of said bag, a first driving means for actuating said conveyor, a second driving means for actuating said mechanism, a member movable in opposite directions, means for imparting movement to said member in one direction, means for imparting movement to said member in a reverse direction, means responsive to predetermined movement of said member in opposite directions for placing both of said driving means respec-

tively into and out of service, and detent means normally permitting sufficient movement of said member in said reverse direction to place only one of said driving means out of service, said detent means being adapted to be released by said bag in the course of its travel on said conveyor to allow continued movement of said member in said reverse direction.

2. In apparatus of the character described, a conveyor adapted to carry a bag having an open end, a mechanism for closing said open end of said bag, a first driving means for actuating said conveyor, a second driving means for actuating said mechanism, a member movable in opposite directions, means for imparting movement to said member in one direction, means for imparting movement to said member in a reverse direction, means responsive to predetermined movement of said member in one direction for placing said first driving means and said second driving means successively into service, said last mentioned means being responsive to predetermined movement of said member in a reverse direction for placing said second driving means and said first driving means successively out of service, and detent means normally permitting sufficient movement of said member in said reverse direction to place only said second driving means out of service, said detent means being adapted to be released by said bag in the course of its travel on said conveyor to allow continued movement of said member in said reverse direction to place said first driving means out of service.

3. In apparatus of the character described, a conveyor adapted to carry a bag having an open end, a mechanism for closing said open end of said bag, a first driving means for actuating said conveyor, a second driving means for actuating said mechanism, a rotary member, means for imparting rotational movement to said member in one direction, means for normally and yieldingly imparting rotational movement to said member in a reverse direction, means responsive to predetermined rotational movement of said member in one direction for placing said first driving means and second driving means successively into service, said last mentioned means being responsive to a predetermined rotational movement of said member in a reverse direction for placing said second driving means and said first driving means successively out of service, and detent means normally permitting sufficient movement of said member in said reverse direction to place only said driving means out of service, said detent means being adapted to be released by said bag in the course of its travel on said conveyor to allow continued rotational movement of said member in said reverse direction to place said first driving means out of service.

4. In apparatus of the character described, a conveyor adapted to carry a bag having an open end, a mechanism for closing said open end of said bag, a first driving means for actuating said conveyor, a second driving means for actuating said mechanism, a rotary member, means for imparting rotational movement to said member in one direction, means for imparting rotational movement to said member in a reverse direction, means responsive to predetermined rotational movement of said member in one direction for placing said first driving means and said second driving means successively into service, said last mentioned means being responsive to predetermined rotational movement of said member in one direction for placing said first driving means and said second driving means successively into service, said last mentioned means being responsive to predetermined rotational movement of said member in

5 8 a reverse direction for placing said second driving means and said first driving means successively out of service, detent means normally permitting sufficient movement of said member in said reverse direction to place only said second driving means out of service, and means for releasing said detent means comprising a device connected to said detent means and extending into the path of travel of said bag on said conveyor, said device being adapted to be actuated by said bag in the course of its travel on said conveyor to release said detent means and allow continued rotational movement of said member in said reverse direction to place said first driving means out of service.

5. In apparatus of the character described, a conveyor adapted to carry a bag having an open end, a mechanism for closing said open end of said bag, a first driving means for actuating said conveyor, a second driving means for actuating said mechanism, a rotary member, means for imparting rotational movement to said member in one direction, means for imparting rotational movement to said member in a reverse direction, means responsive to predetermined rotational movement of said member in one direction for placing said first driving means and said second driving means successively into service, said last mentioned means being responsive to predetermined rotational movement of said member in a reverse direction for placing said second driving means and said first driving means successively out of service, detent means normally permitting sufficient movement of said member in said reverse direction to place only said second driving means out of service, and means for releasing said detent means comprising a device connected to said detent means, resilient means for normally and yieldingly maintaining a portion of said device in the path of travel of said bag, said portion of said device being adapted to be actuated by said bag in the course of its travel on said conveyor to release said detent means against the action of said resilient means to thereby allow continued rotational movement of said member in said reverse direction to place said first driving means out of service.

6. In apparatus of the character described a conveyor adapted to carry a bag having an open end, a mechanism for closing said open end of said bag, a first driving means for actuating said conveyor, a second driving means for actuating said mechanism, a rotary member, means including an arm for imparting rotational movement to said member in one direction, means for normally and yieldingly urging said member in a reverse direction, means responsive to predetermined rotational movement of said member in said one direction for placing said first driving means and said second driving means successively into service, said last mentioned means being responsive to predetermined rotational movement of said member in a reverse direction for placing said second driving means and said first driving means successively out of service, and detent means comprising an element carried by said arm and a pawl movable into and out of locking engagement with said element for normally permitting such movement of said member in said reverse direction to place only said second driving means out of service, said detent means being adapted to be released by said bag in the course of its travel on said conveyor to allow continued rotational movement of said

member in said reverse direction to place said first driving means out of service.

7. In apparatus of the character described, a conveyor adapted to carry a bag having an open end, a mechanism for closing said open end of said bag, a first driving means for actuating said conveyor, a second driving means for actuating said mechanism, a rotary member, means including an arm for imparting rotational movement to said member in one direction, means for normally and yieldingly urging said member in a reverse direction, means responsive to predetermined rotational movement of said member in said one direction for placing said first driving means and said second driving means successively into service, said last mentioned means being responsive to predetermined rotational movement of said member in a reverse direction for placing said second driving means and said first driving means successively out of service, detent means comprising an element carried by said arm and a pawl movable into and out of locking engagement with said element for normally permitting such movement of said member in said reverse direction to place only said second driving means out of service, and means for releasing said detent means comprising a device connected to said pawl and extending into the path of travel of said bag on said conveyor, said device being adapted to be actuated by said bag in the course of its travel on said conveyor to release said pawl from said element and allow continued rotational movement of said member in said reverse direction to place said first driving means out of service.

8. In apparatus of the character described, a conveyor adapted to carry a bag having an open end, a mechanism for closing said open end of said bag, a first driving means for actuating said conveyor, a second driving means for actuating said mechanism, a rotary member, means including an arm for imparting rotational movement to said member in one direction, means for normally and yieldingly urging said member in a reverse direction, means responsive to predetermined rotational movement of said member in said one direction for placing said first driving means and said second driving means successively into service, said last mentioned means being responsive to predetermined rotational movement of said member in a reverse direction for placing said second driving means and said first driving means successively out of service, detent means comprising an element carried by said arm and a pawl movable into and out of locking engagement with said element for normally permitting such movement of said member in said reverse direction to place only said second driving means out of service, means for releasing said detent means comprising a device connected to said pawl, resilient means for normally and yieldingly maintaining a portion of said device in the path of travel of said bag, said portion of said device being adapted to be actuated by said bag in the course of its travel on said conveyor to disengage said pawl from said element against the action of said resilient means to thereby allow continued rotational movement of said member in said reverse direction to place said first driving means out of service.

9. In apparatus of the character described, a conveyor adapted to carry an article along a substantially horizontal path, driving means for said conveyor, movable connector means for placing said driving means and said conveyor into and

out of operative engagement, actuating means including a first rotary shaft for imparting movement to said connector means, a second rotary shaft, detent means comprising a notched element rotatable with one of said shafts and a pawl rotatable with the other of said shafts, said pawl engaging the notched portion of said element when said first shaft is in a predetermined angular position, and a device secured to and rotatable with said second shaft and extending into the path of travel of said article on said conveyor, said device being adapted to be actuated by said article in the course of its travel on said conveyor to impart rotation to said second shaft and to effect relative movement between said element and said pawl.

10. In apparatus of the character described, a conveyor adapted to carry an article along a substantially horizontal path, driving means for said conveyor, movable connector means for placing said driving means and said conveyor into and out of operative engagement, actuating means including a first rotary shaft and resilient means for respectively imparting movement to said connector means in one direction and in a reverse direction, a second rotary shaft, releasable detent means coacting with said actuating means for maintaining said connector means in a position to effect operative engagement between said driving means and said conveyor, said detent means comprising a notched element rotatable with one of said shafts and a pawl rotatable with the other of said shafts, and a device secured to and rotatable with said second shaft and extending into the path of travel of said article on said conveyor, said device being adapted to be actuated by said article in the course of its travel on said conveyor to impart rotation to said second shaft and effect disengagement between said element and said pawl.

11. In apparatus of the character described, a conveyor adapted to carry an article along a substantially horizontal path, driving means for said conveyor, movable connector means for placing said driving means and said conveyor into and out of operative engagement, actuating means including a first rotary shaft and resilient means for respectively imparting movement to said connector means in one direction and in a reverse direction, a second rotary shaft, releasable detent means coacting with said actuating means for maintaining said connector means in a position to effect operative engagement between said driving means and said conveyor, said detent means comprising a notched element rotatable with said first shaft and a pawl rotatable with said second shaft, and a device secured to and rotatable with said second shaft and extending into the path of travel of said article on said conveyor, said device being adapted to be actuated by said article in the course of its travel on said conveyor to impart rotation to said second shaft and effect removal of said pawl from the notched portion of said element.

12. In apparatus of the character described, a conveyor adapted to carry an article along a substantially horizontal path, driving means for said conveyor, movable connector means for placing said driving means and said conveyor into and out of operative engagement, actuating means including a first rotary shaft for imparting movement to said connector means in one direction, a rod secured to said first rotary shaft and rotatable therewith, a second rotary shaft, detent means comprising a notched element carried by

11

said rod and a pawl rotatable with said second rotary shaft, and means secured to and rotatable with said second shaft and adapted to be actuated by said article in the course of its movement on said conveyor for releasing said pawl from said element.

13. In apparatus of the character described, a conveyor adapted to carry an article along a substantially horizontal path, driving means for said conveyor, movable connector means for placing said driving means and said conveyor into and out of operative engagement, actuating means including a first rotary shaft for imparting movement to said connector means in one direction, a rod secured to said first rotary shaft and rotatable therewith, a second rotary shaft, detent means comprising a notched element carried by said rod and a pawl rotatable with said second rotary shaft, a device secured to and rotatable with said second shaft adapted to be actuated

by said article in the course of its travel on said conveyor to release said detent means, and means for actuating said connector means upon release of said detent means to render engagement between said driving means and said conveyor ineffective.
